UNITED STATES PATENT OFFICE.

GURNEY ENOCH WARD, OF ABILENE, TEXAS.

TROLLEY.

No. 826,296.

Specification of Letters Patent.

Patented July 17, 1906.

Application filed August 11, 1905. Serial No. 273,784.

To all whom it may concern:

Be it known that I, GURNEY ENOCH WARD, a citizen of the United States, and a resident of Abilene, in the county of Taylor and State of

5 Texas, have invented a new and Improved Trolley, of which the following is a full, clear, and exact description.

The object of the invention is to provide a trolley in which the liability to running off 10 the trolley-wire is reduced to a minimum, and I attain this end by a peculiar construction which involves a trolley-wheel carried on an axis fixed on the trolley pole or harp and an auxiliary wheel yieldingly mounted 15 on the pole and pressed against the under side of the wire, so that should the pole drop slightly the auxiliary wheel will move relatively to the pole and reduce this contact with the wire.

20 The invention resides in certain novel features of construction and arrangement of parts, which will be fully set forth hereinafter, and particularly pointed out in the claims.

Reference is had to the accompanying 25 drawings, which illustrate as an example the preferred embodiment of my invention, in which drawings like characters of reference indicate like parts in both views, and in which—

30 Figure 1 is a section on the line 1 1 of Fig. 2, and Fig. 2 is a side elevation with parts broken away.

10 indicates the trolley-pole, which is supplied with a harp or end portion 11 of any desired construction.

12 indicates the main trolley-wheel, which is mounted in the harp 11 on a fixed axle 14. The auxiliary trolley-wheel 15 is carried on a pin 16, which is held in a fork 17 at the end of 40 a rod 18. Said rod is slidably fitted within a tube 19, secured in the harp 11. The tube carries a pin 20, which fits in the slide 21 of the rod 18, which prevents the rod from turning, and thus maintaining the rod 18 in true 45 contact with the trolley-wire. Encircling the rod 18 within the tube 19 is a spring 22, the lower end of which engages the flange 23 and the upper end of which engages the fork 17. This spring is of the expansive type and 50 holds the rod 18 steadily engaged with the trolley-wire. 24 indicates the cord or rope for drawing the trolley-pole down out of contact with the wire, and this cord has a branch 25, which is connected to the lower 55 end of the rod 18, so when tension is exerted

on the cord the pole is moved bodily downward, and at the same time the auxiliary wheel is given an independent downward movement.

In using the invention the trolley is mounted in the usual manner, and the wheels 12 and 15 run along the under side of the wire. Both of the wheels serve as conductors for electric fluid, and owing to the peculiar manner in which the wheel 15 is mounted the auxiliary wheel retains its true engagement with the trolley-wire irrespective of jumping or swinging of the pole. When it is desired to draw down the pole for the purpose of clearing crossings and other head structures, the 60 cord 24 should be pulled, so that when the pole is moved down the auxiliary wheel 15 also moves snugly down in the harp, so that it does not project above the wheel 14. This avoids entangling the auxiliary wheel with 65 overhead structures when the pole is drawn down. The spring-sustained wheel 15 will bear yieldingly against the wire at all times during the operation of the trolley and will take from the same the shock incident to 70 vertical movement of the trolley against the wire.

It will be noticed that the auxiliary-wheel-supporting rod is so mounted on the harp that it moves approximately tangent to the 75 arc of the circle described by the end of the pole and as a consequence will respond more quickly to the impulse of the spring and will require less time to pass through the entire extent of movement with respect to the harp 80 necessary to maintain the said wheel in contact with the trolley-wire than were it mounted to move perpendicular thereto. In the latter case the wheel would have a greater extent of movement and more or less friction 85 would result between the rod and its connections.

Having thus described the preferred form of my invention, what I claim as new, and desire to secure by Letters Patent, is—

1. A trolley having a pole provided with a harp, a wheel mounted therein on a permanent axis, a sleeve secured within the harp and at approximately a right angle to the pole, a rod having a forked end mounted 105 within the sleeve, an auxiliary wheel journaled in the fork, a spring acting between the sleeve and fork, and a cord connected with the pole and having a branch connected with the end of the rod.

100

105

110

2. A trolley having a pole provided with a harp, a wheel mounted therein on a permanent axis, a spring-actuated rod slidably mounted within the harp and movable at approximately right angles to the pole, an auxiliary wheel journaled in the end of the rod, and a cord connected with the pole and rod.

In testimony whereof I have signed my name to this specification in the presence of two subscribing witnesses.

GURNEY ENOCH WARD.
